(57) **CLAIM**

The ornamental design for a waterproof power coupler, as shown and described.

DESCRIPTION

FIG. 1 is a top perspective view of a waterproof power coupler according to the present design;

FIG. 2 is a front view of the waterproof power coupler of FIG. 1;

FIG. 3 is a left side view of the waterproof power coupler of FIG. 1;

FIG. 4 is a rear view of the waterproof power coupler of FIG. 1;

FIG. 5 is a right side view of the waterproof power coupler of FIG. 1;

FIG. 6 is a top perspective view of the waterproof power coupler of FIG. 1 when the waterproof power coupler is open;

FIG. 7 is a front view of the waterproof power coupler of FIG. 6;

FIG. 8 is a left side view of the waterproof power coupler of FIG. 6;

FIG. 9 is a rear view of the waterproof power coupler of FIG. 6; and,

FIG. 10 is a right side view of the waterproof power coupler of FIG. 6.

1 Claim, 10 Drawing Sheets
